Primary Examiner — Karen E Kearney

(74) Attorney, Agent, or Firm — Banner & Witcoff, Ltd.

(57) **CLAIM**

The ornamental design for a display screen with icon showing the new design;

FIG. 1 is a front view of a display screen with icon showing the new design;
FIG. 2 is a front view of a display screen with icon showing an alternative embodiment of the new design; and,
FIG. 3 is a front view of a display screen with icon showing the design of FIG. 1 on a device.

The broken line showing of the remainder of the user interface and the remainder of the display screen is for environmental purposes only and forms no part of the claimed design.
